FENCE POST SETTING AND PULLING RIG

James W. Jordan, Tallulah, La., assignor of fifty
per cent to L. W. Burgess, Tallulah, La.

Application July 24, 1950, Serial No. 175,518

6 Claims. (Cl. 254—29)

1

This invention relates to new and useful improvements in fence post setters and pullers.

The primary object of this invention is to adapt the blade of a conventional bulldozer for both the setting and pulling of fence posts without requiring any dismantling of the bulldozer or permanent modification thereof.

Another important object of this invention closely allied to the preceding object is to provide a simple and inexpensive attachment that may be efficaciously attached to and removed from a bulldozer blade, and which will utilize the means provided for elevating and lowering the blade for pulling or driving fence posts.

Other important objects of this invention is to provide an attachment capable of realizing the foregoing objects, and which, in use, will require only that the bulldozer travel in a straight course past fence-post positions either directly over the fence line or to the side of the fence line, stopping only momentarily at each fence post position to complete its function.

A meritorious feature of the present invention is the means provided for securing the attachment to the bulldozer blade, which requires only one man for either securing or removing the attachment from the bulldozer blade.

Still other important features of the present invention, the last to be specifically enumerated herein, resides in the extreme simplicity, the ruggedness, and the efficiency of the attachment for the purposes intended.

These, together with various ancillary features and objects of the invention which will later become apparent as the following description proceeds, are attained by the present invention, a preferred embodiment of which has been illustrated by way of example only in the accompanying drawings, wherein:

Figure 1 is a side elevational view of a bulldozer with the present invention attached thereto and in position for driving a fence post;

Figure 2 is a front elevational view of the machine shown in Figure 1;

Figure 3 is a vertical longitudinal sectional view of the present invention showing the same attached to a bulldozer blade, also in section, and showing the same elevated for commencing the driving of a fence post with the lowered position of the same being shown in dotted outline;

Figure 4 is a view similar to Figure 3, and in which the attachment is shown as including a

further component in use for pulling fence posts;

Figure 5 is a perspective view of the attachment forming the subject matter of the present invention; and

Figure 6 is a fragmentary view of the attachment partially shown in section.

Reference is now made more specifically to the accompanying drawings, wherein like numerals designate similar parts throughout the various views, and in which the numeral 10 designates a bulldozer generally having an engine 12, operator's seat 14, driving track 16, and a blade 18 carried by push bars 20 that are pivoted at their rear ends at 22 for vertical swinging movement.

The bulldozer 10 includes means for forcibly elevating and depressing the push bars 20 and the bulldozer blade 18, which means include a bellcrank having arms 24 and 26 pivoted at 28 to the frame of the bulldozer 10, the bulldozer carrying a double-acting hydraulic jack 30 that is connected to the arm 26, and a link 32 connecting the arm 24 to the push bars 20. It will be understood that a bellcrank and a hydraulic jack are provided for each of the push bars 20, and that suitable means are provided, not shown, whereby the hydraulic jacks 30 may be operated from the operator's seat 14 to act in unison or independently, as desired.

The attachment forming the subject matter of the present invention is designated generally at 34 and includes a pair of I-beam uprights 36 and an I-beam driving head 38 welded to the front sides of the uprights 36 at their upper ends, the driving head 38 projecting laterally beyond the uprights 36 for a purpose to be presently explained.

As clearly shown in Figures 1 and 5, a pair of brace rods 40 are provided for stabilizing the driving head 38 in relation to the uprights 36 which connect the forward face of the driving head 38 to the lowermost front portion of the uprights 36, each of the brace rods 40 lying in the same longitudinal vertical plane of the upright to which it is attached.

As clearly shown in Figures 4 and 5, a pair of arms formed of I-beams 42 are welded to the lower ends of the uprights 36 and extend in spaced parallel relation upwardly and rearwardly from the bottom ends of the uprights 36, the connections between the arms 42 and the uprights 36 being reinforced by a pair of plates 44 underlying the lowermost extremities of the uprights 36 and welded to the uprights and to the forward

extremities of the arms 42. In addition, the arms 42 are maintained in spaced parallel relation by a pair of reinforcing bars 46 extending between the forward and rear ends of the arms 42 and are suitably welded thereto. Intermediate their ends, each of the uprights 36 is also provided with rearwardly extending arms 48 of I-beam construction, the arms 48 having their ends adjacent the uprights 36 pivoted on bolts 50 extending between the rearmost portion of pairs of ears 52 secured to the opposite sides of the uprights 36. It will be understood that the ears 52 are welded to the uprights 36 and that if desired spacing blocks, not shown, may be received between the ears 52 and the web portions of the uprights 36.

In order to secure the attachment 36 to the bulldozer blade 18, each of the arms 48 has welded to its undersurface intermediate its ends a pair of spaced cleats 54, and the rear extremity of each of the arms 42 and 48 has secured thereto a short length of chain 56, as clearly shown in Figure 5. As best shown in Figure 4, in securing the attachment 34 to the bulldozer blade 18, the lower edge of the bulldozer blade 18 is received within the apex of the angle formed between the uprights 36 and the arms 42, and the upper edge of the bulldozer blade 18 is received between the cleats 54 carried by the arms 48, the arms 48 being swung downwardly upon their pivots 50 to securely clamp the blade 18 between the arms 42 and 48 and the rearmost extremities of the arms 42 and 48 are secured by means of load binders 58 connecting the chain links 56.

For a purpose presently to appear, it will be seen in Figure 6 that the driving head 38 which includes flanges 60 connected by a web 62 is provided with a pair of spaced ribs 64 secured to the underside of the web 62 transverse to the longitudinal dimension of the driving head 38.

The manner of attaching the attachment 34 to the bulldozer blade and the method of its use will be readily understood. In attaching the attachment, the frame is placed upon the ground with the arms 42 flat on the surface of the ground, and with the chain links 56 disconnected and the arms 48 swung upwardly. The bulldozer is then driven toward the attachment and the bulldozer blade 18 lowered until the lower edge thereof rests in the apex of the angle formed by the arms 42 and the uprights 36, whereupon the operator of the bulldozer may dismount and swing the arms 48 downwardly until the upper edge of the bulldozer is received between the cleats 54 and the load binder secured. It will be understood that the attachment may be efficaciously removed by reversing the above procedure.

As shown in Figure 3, a post 66 may be driven by placing the lower end against the ground and placing the upper end thereof between the flanges 60 and the ribs 64 of the driving head 38 with the bulldozer blade raised, and then operating the hydraulic jacks 30 to force lowering movement of the bulldozer blade, whereupon the driving head 38 forces the post 66 into the ground, it being noted that sufficient force may be exerted against the post 66 that in soil of normal consistency the lower end of the post 66 need not necessarily be pointed. In raising the post 66 from the ground, attention is directed to Figure 4, wherein it will be seen that a chain 68 is provided having its upper end detachably secured about the driving head 38, as at 70, and the lower end of which chain 68 may be looped about the post 66, as at 72. As will be understood, the chain 68 is secured to the post 66 when the bulldozer

blade is lowered, whereupon raising the bulldozer blade by the use of the jacks 30, the post 66 may be raised to the position shown in Figure 4.

It will be appreciated that by the means provided for securing the attachment to the bulldozer blade that the attachment may be secured centrally to the bulldozer blade as shown in Figure 2, or if desired the attachment may be secured adjacent either one of the ends of the bulldozer blade with equal facility, in which latter position one of the ends of the driving head 38 will project laterally beyond the sides of the bulldozer and its blade. Accordingly, it will be appreciated that in either setting or pulling fence posts the bulldozer 10 may be driven either forwardly or rearwardly along the fence line with the driving head 38 of the attachment projecting laterally to engage the fence post. Of course, in driving the fence post the bulldozer may be backed down directly along the fence line when the attachment is centrally secured to the bulldozer blade, for in such operation none of the upstanding fence posts will be disposed in the path of the bulldozer.

Since, from the foregoing, the construction and advantages of invention are readily apparent, further description is believed to be unnecessary.

However, since numerous modifications and equivalents will readily occur to those skilled in the art after a consideration of the foregoing specification and accompanying drawings, it is not intended to limit the invention to the exact embodiment shown and described, but all suitable modifications and equivalents may be resorted to which fall within the scope of the appended claims.

Having described the invention, what is claimed as new is:

1. A machine for setting fence posts comprising a bulldozer including a blade and means for elevating and lowering the blade, a post driving assembly comprising a frame including a pair of spaced upright members, a driving head connecting said members adjacent their upper ends, a pair of vertically spaced upper and lower bars extending rearwardly of each of said upright members, one of said bars of each pair thereof being pivotally connected to the upright member for swinging movement towards the other bar and releasably clamping the blade therebetween and securing means releasably connecting each upper and lower bar adjacent their rearmost extremities.

2. The combination of claim 1, wherein the upper bars have a pair of spaced cleats receiving the upper edge of the blade therebetween to prevent relative sliding movement between the upper bars and the blade, the lower edge of the blade being received in the apices of the angles formed by the lower bars and the upright members.

3. A fence post setting attachment for use with bulldozers of the type having a blade and elevating means therefor, comprising a frame including a horizontally disposed driving head, vertically spaced pairs of upper and lower bars secured to the frame and extending rearwardly therefrom for receiving a bulldozer blade therebetween, the upper bars of said pairs of bars being pivoted to said frame for swinging movement towards the lower bars, and securing means for releasably holding the bars in clamping engagement with a bulldozer blade.

4. The combination of claim 3 including means

carried by the driving head for engaging a fence post to withdraw the latter from the soil upon lifting the attachment.

5. A fence post setting attachment mounted for vertical swinging movement comprising a pair of spaced upright members, a driving head connecting the members adjacent their upper ends, vertically spaced pairs of upper and lower bars secured to and extending rearwardly of the upright members, the upper bars of said pairs of bars being pivotally connected to the upright members for swinging towards the lower pair of bars, means for connecting the rear ends of the upper bars to the rear ends of the lower bars for releasably and adjustably holding the upper bars against swinging movement away from the lower bars, means for raising and lowering the said attachment.

6. The combination of claim 5, wherein said lower bars define acute angles with the upright 10

members opening towards the upper bars, said upper bars each having a pair of spaced cleats on its under side, whereby a bulldozer blade may have its upper edge retained by the cleats and its lower edge retained in the apices of the acute angles.
